BOX FOR CHRISTMAS TREE LIGHTS

David W. Fisherman, New York, N. Y., assignor to New York Merchandise Co., Inc., New York, N. Y., a corporation of New York

Application July 2, 1956, Serial No. 42,115

Term of patent 14 years

(Cl. D58—12.6)

Fig. 1

Fig. 2

Figure 1 is a front perspective view of a box for Christmas tree lights showing my new design; and Figure 2 is a side elevational view thereof shown in open position.

The rear and end views of the box not shown are plain.

The dominant features of my design reside in the portions shown in full lines.

I claim:

The ornamental design for a box for Christmas tree lights, as shown and described.
